CLAIM

The ornamental design for a fuse holder, as shown and described.

DESCRIPTION

FIG. 1 is a front view of a fuse holder showing our new design.

FIG. 2 is a rear view of the fuse holder.

FIG. 3 is a top view of the fuse holder.

FIG. 4 is a bottom view of the fuse holder.

FIG. 5 is a left side view of the fuse holder.

FIG. 6 is a right side view of the fuse holder.

FIG. 7 and FIG. 8 are perspective views of the fuse holder; and,

FIG. 9 is a sectional view along the line IX—IX in FIG. 5, wherein the fuse holder is shown in a connecting condition. The fuse holder is mounted on a printed circuit board and receives a blade type fuse. The printed circuit board and the fuse are drawn in broken lines for illustrative purposes only and form no part of the claimed design.
